(57) CLAIM

The ornamental design for a storage compartment with hinged face plate for empty computer bay, as shown and described.

DESCRIPTION

FIG. 1 is a perspective view of the storage compartment with hinged face plate for empty computer bay embodying the design of the present invention;

FIG. 2 is a front elevational view thereof;

FIG. 3 is a rear elevational view thereof;

FIG. 4 is a right side elevational view thereof, the left side elevational view being a mirror image thereof;

FIG. 5 is a top plan view thereof;

FIG. 6 is a bottom plan view thereof;

FIG. 7 is a reduced, perspective view showing the storage compartment with hinged face plate being inserted into an empty computer bay; the broken lines depict environmental structure and form no part of the claimed design; and,

FIG. 8 is a reduced, perspective view of the storage compartment showing the hinged face plate opened to provide access thereto.
